US0D1073180S

(12) **United States Design Patent** (10) Patent No.: **US D1,073,180 S**
(45) Date of Patent: ** Apr. 29, 2025

(54) SNUS CAN

- (71) Applicant: **Philip Morris Products S.A.**,
Neuchâtel (CH)
- (72) Inventor: **Steven Shainwald**, Lausanne (CH)
- (73) Assignee: **Philip Morris Products S.A.**,
Neuchâtel (CH)
- (**) Term: **15 Years**
- (21) Appl. No.: **29/869,204**
- (22) Filed: **Dec. 23, 2022**
